(57) **CLAIM**

The ornamental design for a high-pressure spray gun, as shown and described.

DESCRIPTION

FIG. 1 is a front, right and top perspective view of the first embodiment of a high-pressure spray gun, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is an enlarged view of portion of FIG. 1 thereof;

FIG. 10 is an enlarged view of portion of FIG. 1 thereof; and

FIG. 11 is a front, right and top perspective view shown in an environment of use.

FIG. 12 is a front, right and top perspective view of the second embodiment of the high-pressure spray gun;

FIG. 13 is a rear, left and bottom perspective view thereof;

FIG. 14 is a front view thereof;

FIG. 15 is a rear view thereof;

FIG. 16 is a left side view thereof;

FIG. 17 is a right side view thereof;

FIG. 18 is an enlarged top plan view thereof;

FIG. 19 is an enlarged bottom plan view thereof;

FIG. 20 is an enlarged view of portion of FIG. 12 thereof;

FIG. 21 is an enlarged view of portion of FIG. 12 thereof; and,

FIG. 22 is a front, right and top perspective view shown in an environment of use.

The dot-dash broken lines surrounding details shown in FIGS. 1, 9-10, 12, and 21-22 are for the purpose of annotating the enlarged views only and form no part of the claimed design. The evenly spaced broken lines illustrate portions of the high-pressure spray gun that form no part of the claimed design. The additional evenly spaced broken lines in FIGS. 11 and 22 depict environmental subject matter and form not part of the claimed design.
